REEL SUPPORT

William R. Spiller and Leo D. Barley, Dayton, Ohio, assignors, by mesne assignments, to Acme Steel Company, Chicago, Ill., a corporation of Illinois

Original application May 31, 1943, Serial No. 489,116, now Patent No. 2,398,053, dated April 9, 1946. Divided and this application May 4, 1945, Serial No. 591,898

10 Claims. (Cl. 242—134)

1

This invention relates to wire stitching machines and more particularly to the support for the wire reel which is used with such machines.

It is the principal object of the invention to provide in a wire stitching machine a support or a mounting mechanism for the wire containing reel which remains attached to the machine at all times and which is moveable from its operative to an inoperative position to make possible the removal of an empty reel and the replacement thereof with a full reel, quickly and easily and with a minimum of work on the part of the operator.

It is a further object to provide a reel support for a stitching machine which is readily adjustable in a simple and effective manner to receive reels of different sizes and to develop an adjustable and predetermined resistance or drag upon the unwinding action of the reel.

It is also an object to provide such a reel support having an adjustable and predetermined tension or drag upon the unwinding action of the reel which is not affected by the replacement of the reel, being reestablished at the desired value immediately upon the replacement of the empty reel with a full reel.

Other objects and advantages will be apparent from the following description, the accompanying drawings, and the appended claims.

In the drawings,

Fig. 1 is a view in perspective looking toward a wire stitching machine constructed in accordance with the present invention as viewed from the operators position and showing the machine in inverted position;

Fig. 2 is a view in section through the reel supporting mechanism;

Fig. 3 is a detail sectional view of the latch mechanism for the reel support on the line 3—3 of Fig. 2; and

Fig. 4 is a detail view in elevation looking toward the reel support in the direction of the arrows 4—4 of Fig. 2.

Referring to the drawing which discloses a preferred embodiment of the invention, the machine is shown as being substantially completely enclosed within a housing or casing 10. The casing is enlarged at its forward end as shown at 11 to provide for receiving a stitcher head 13 therein, such stitcher head being of usual construction and not requiring further detailed description.

A clincher arm 15 is supported from the casing 10, the entire structure being rotatably mounted in a ring-shaped split clamp 16 which provides

2

for rotation of the entire mechanism about a horizontal axis. The machine may be supported by means of a rod 17 attached to the clamp ring 16, and having a hook 18 by means of which it may be suspended from an overhead support such as a cable, crane, or other suitable means.

The drive motor shown at 20 is also supported from and rotatable with casing 10, the motor being controlled by switch 21, and suitable hand 10 grips 22 and 23 incorporate additional control over the actuation of the machine and facilitate its proper manipulation. The machine is shown and described more fully in parent application Serial No. 489,116, filed May 31, 1943, now Patent 15 No. 2,398,053 of which the present application is a division.

With a machine of the present construction it becomes necessary to replace the reel containing the wire which is fed to the stitcher head 20 mechanism more or less frequently, and it is desirable to be able to do so rapidly and easily and without altering the tension or drag which is applied to the reel after the machine has been properly adjusted. Such drag on the reel is desirable to prevent overrunning of the reel and to maintain a substantially uniform tension in the wire as it is unwound by the action of the stitcher head drawing the wire therefrom. For this purpose a stud or pin 30 projects outwardly from the casing from which is rotatably mounted a reel engaging clamp member 31, the dished central part thereof providing clearance to receive the usual nut on the outer face of the reel itself. The outer part of clamp member 31 is formed 35 with a plurality of outwardly directed flanged fingers 32 which engage and bear against the face of the spool or reel 33 well outwardly of the axis thereof. The clamp member 31 is urged against the face of the reel by spring 34 which bears 40 against a friction surface 35 on the lower face of clamp member 32; movement of the member 31 on stud 30 is limited by means of a collar 36 on the upper end of the stud.

A similar dished clamp or engaging member 45 38 is rotatably mounted in a socket 39 formed in bracket 40, a cooperating pin 41 secured in the bracket having a flange 42 thereon for retaining the parts in assembled relation. Clamp member 38, like member 31, engages the side surface of the reel and is rotated therewith as the wire is withdrawn by the operation of the machine, the desired frictional drag force being developed at the relatively moving surfaces where member 38 is supported in its socket 39, such surface being indicated at 43.

Bracket 40 is adjustably supported by arm 44 which has an elongated slot 45 therein through which there project the screws 46 secured to the end of the bracket. By loosening the screws, the bracket may be moved on the arm thereby moving clamp 38 closer to or farther from clamp 32, and adapting the mechanism for receiving reels of different width. Movement of the bracket under pressure with both clamps in contact with the reel will also vary the tension in spring 34, with the result that the frictional drag developed by the rotation of the clamp members in their supports will also be varied, the setting of the bracket arm thus providing a means for predetermining and adjusting the frictional drag during the unwinding action of the reel.

Arm 44 is pivotally mounted on pin 48 carried by part of the casing of the machine and on the downwardly extended part 49 thereof carries a latch plunger 50 urged by spring 51 to latching engagement with a fixed abutment 52. The latch may be manually withdrawn by means of handle part 53 to release the plunger and to provide thereby for the swinging of the arm and the bracket to a release position where the reel may be removed and replaced between the clamp members. With the construction as disclosed, this operation does not bring about any change in the frictional drag imposed on the unwinding of the reel, the insertion of a fresh reel and the latching of the upper bracket into its operative position as shown providing for reestablishment of the tension originally present. This operation requires no adjustment or other manipulation on the part of the operator and is completed by the simple movement of the bracket into its operative position in which it is automatically latched and held until released. It will be further noted that all portions of the reel engaging mechanism are mounted in fixed relation with respect to the casing and hence will not be lost or misplaced at any time during the various uses of the machine.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. In a wire stitching machine the combination of a reel support comprising a clamp member for one side of the reel, means supported in fixed relation with respect to said machine for rotatably mounting said member for rotation with the reel as the wire is unwound therefrom, a second clamp member mounted on said machine independently of said first clamp member for engaging the opposite side of said reel, means pivotally mounted on said machine having a predetermined operative position for adjustably mounting said second clamp member in engaging relation with said opposite side of the reel, and means for releasably retaining said pivotally mounted means in said operative position and providing for quick release thereof to effect removal and replacement of said reel.

2. In a wire stitching machine the combination of a reel support comprising a clamp member for one side of the reel, means supported in fixed relation with respect to said machine for rotatably mounting said member for rotation with the reel as the wire is unwound therefrom, a second clamp member for engaging the opposite

side of said reel, means mounted on said machine having an operative position for adjustably mounting said second clamp member in engaging relation with said opposite side of the reel, means for releasably retaining said mounting means in said operative position and providing for quick release thereof to effect removal and replacement of said reel, and means for restraining rotation of at least one of said members to establish a drag on the unwinding action of the reel.

3. In a wire stitching machine the combination of a reel support comprising a clamp member adapted to engage one side of a reel, means for rotatably mounting said clamp member upon said machine for rotation with the reel as the wire is unwound therefrom, a second clamp member mounted on said machine independently of said first clamp member for engaging the opposite side of the reel, means pivotally carried by said machine and having an operative position for mounting said second clamp member in engaging relation with the opposite side of the reel for rotation therewith as the wire is unwound therefrom, and means for adjusting the spacing of said second clamp on its said mounting means to change its relation with said first mentioned clamp member in said operative position thereof to receive reels of different width therebetween.

4. In a wire stitching machine the combination of a reel support comprising a clamp member adapted to engage one side of a reel, means for rotatably mounting said clamp member upon said machine for rotation with the reel as the wire is unwound therefrom, a second clamp member for engaging the opposite side of the reel, means carried by said machine and having a predetermined operative position for adjustably mounting said second clamp member in engaging relation with the opposite side of the reel for rotation therewith as the wire is unwound therefrom, means for releasably retaining said mounting means in said operative position and provide for quick release thereof to effect removal and replacement of said reel, means for subjecting at least one of said clamp members to a predetermined friction upon rotation thereof to establish a predetermined tension in the wire supplied to said machine, said friction being automatically reestablished at the predetermined value upon the assembly of said clamp members and said reel in said predetermined operative position.

5. In a wire stitching machine of the character described, the combination of a reel support comprising clamp members for receiving the reel therebetween, means for rotatably mounting said clamp members upon said machine for rotation with the reel as the wire is unwound therefrom, adjustable means for supporting one of said clamp members for movement to an inoperative position to provide for removal and replacement of said reel and to a predetermined operative position in which one of said clamp members is in fixed spacing relative to the other said clamp member, said adjustable means and its associated clamp member remaining attached to said machine in said inoperative position, means for releasably retaining said adjustable supporting means in said predetermined operative position, and yieldable means separate from said retaining means for urging said clamp members towards each other in clamping engagement with said reel and cooperating with said clamp mem-

bers and said mounting means to provide tension resisting unwinding of said reel.

6. In a wire stitching machine of the character described the combination of a reel support comprising clamp members for receiving the reel therebetween, yieldable means carried by one of said clamp members for urging said clamp members toward each other in operative position in clamping engagement with the reel, adjustable means for supporting the other of said clamp members for movement to an inoperative position to provide for removal and replacement of said reel, means for releaseably retaining said adjustable supporting means in a predetermined operative position, means for adjusting the spacing between said clamp members in said operative position to predetermine the tension in said yieldable means and to provide for receiving reels of different width, and friction means establishing a frictional drag upon the rotation of at least one of said clamp members varying with the tension existing in said yieldable means.

7. In a wire stitching machine of the character described the combination of a reel support comprising clamp members for receiving the reel therebetween, yieldable means for urging said clamp members toward each other in clamping engagement with the reel, adjustable means for supporting one of said clamp members for movement to an inoperative position to provide for removal and replacement of said reel and to a predetermined operative position in which said one clamp member is in fixed spacing relative to the other said clamp member, means for releaseably retaining said adjustable supporting means in said operative position, means for adjusting the spacing between said clamp members to predetermine the tension in said yieldable means and to provide for receiving reels of different width, means for releasing said adjustable supporting means to allow movement thereof to said inoperative position providing for replacement of the reel, said adjustable supporting means when returned to its said operative position reestablishing the tension in said yieldable means at said predetermined value to maintain a desired frictional drag upon the rotation of the reel.

8. In a stitching machine of the character described having an enclosing casing adapted to receive stitching mechanism therein, the combination of means on said casing for removably and replaceably supporting a wire reel enclosing a stud fixed to and projecting outwardly from said casing, a clamp member rotatably supported on said stud and adapted to engage the side of the reel for rotation therewith, a cooperating pin, means for pivotally supporting said pin in opposed relation with respect to said stud, a clamp member rotatably supported on said pin and adapted to engage the opposite side of the reel and to be rotated therewith, yieldable means for urging said clamp members toward each other and into engagement with the opposite sides of the reel, frictional means effective between at least one of said clamp members and its support for resisting the unwinding action of the reel, and latch means providing for the withdrawal of said pin for removal and replacement of the reel while maintaining a predetermined frictional drag upon a replacement reel during the unwinding thereof.

9. In a stitching machine of the character described having an enclosing casing adapted to

receive stitching mechanism therein, the combination of means on said casing for removably and replaceably supporting a wire reel including a stud fixed to and projecting outwardly from the casing, a clamp member rotatably mounted on said stud and adapted to engage one side of the reel for rotation therewith, yieldable means for urging said clamp outwardly of said stud and into engagement with the reel, a cooperating pin, means for pivotally supporting said pin in opposed relation with respect to said stud providing for receiving the reel therebetween, a clamp member rotatably mounted on said pin, a friction element effective between one of said clamp members and the mounting thereof adapted to establish a variable frictional drag to restrict the unwinding of the reel in accordance with the pressure effective upon said clamp member and its said supporting means, and means for adjusting said supporting means to establish a predetermined pressure urging said clamp members toward each other creating a predetermined frictional drag upon the unwinding of said reel.

10. In a stitching machine of the character described having an enclosing casing adapted to receive stitching mechanism therein, the combination of means on said casing for removably and replaceably supporting a wire reel including a stud fixed to and projecting outwardly from the casing, a clamp member rotatably mounted on said stud and adapted to engage one side of the reel for rotation therewith, yieldable means for urging said clamp outwardly of said stud and into engagement with the reel, a cooperating pin, means for pivotally supporting said pin in opposed relation with respect to said stud providing for receiving the reel therebetween, a clamp member rotatably mounted on said pin, a friction element effective between one of said clamp members and the mounting thereof adapted to establish a variable frictional drag to restrict the unwinding of the reel in accordance with the pressure effective upon said clamp member and its said supporting means, and means for adjusting said supporting means to establish a predetermined pressure urging said clamp members toward each other creating a predetermined frictional drag upon the unwinding of said reel.
